(57) **CLAIM**

The ornamental design for a nozzle for dishwasher as shown and described.

DESCRIPTION

1. Nozzle for dishwasher

1.1 : Perspective

1.2 : Front

1.3 : Back

1.4 : Left

1.5 : Right

1.6 : Top

1.7 : Bottom

1.8 : Perspective view 2

The broken lines depict portions of the nozzle for dishwasher that form no part of the claimed design; reproduction 1.8 is a perspective view showing the state of use that the claimed design has been installed at the bottom inside of a dishwasher; as shown in reproduction 1.8, the subject design is used by being installed on the bottom of the dishwasher in order to jet water and detergent; the top surface of the subject design is curved so that water can flow without pooling on the top part; the subject design has jet holes facing different directions to improve functionality.
